UNITED STATES PATENT OFFICE.

EDGAR I. COOMBS, OF PROVIDENCE, RHODE ISLAND, ASSIGNOR TO B. A. BALLOU AND COMPANY, INC., OF PROVIDENCE, RHODE ISLAND, A CORPORATION OF RHODE ISLAND.

BRACELET.

1,141,614.

Specification of Letters Patent.

Patented June 1, 1915.

Application filed April 8, 1913. Serial No. 758,620.

To all whom it may concern:

Be it known that I, EDGAR I. COOMBS, a citizen of the United States, and resident of the city of Providence, in the county of Providence and State of Rhode Island, have invented certain new and useful Improvements in Bracelets, of which the following is a specification.

This invention relates to bracelets of the class constructed of two tubular sections hinged together and provided with a spring check for frictionally retaining the free ends of the bracelet together.

The invention further consists in providing a guard for limiting the opening swing of their free ends on said hinge, and the object of the invention is to provide such a bracelet with a guard member having one end fixed to one of the tubular sections and provided with one or more spring fingers or members adapted to be engaged by portions of the other section for releasably securing the sections in closed position. It is usual in bracelets of this class to have a positive lock for securing these ends together, the same being provided with a thumb nail presser pin to release the lock, but by my improved construction the necessity of this operation is obviated as the ends are releasably retained by the action of a spring detent, which will normally hold the bracelet ends firmly in closed position but which will yield to an excessive pull and permit the ends to separate for the purpose of opening the bracelet to be readily passed over the hand of the wearer.

With these and other objects in view, the invention consists of certain novel features of construction, as will be more fully described and particularly pointed out in the appended claims.

Of the accompanying drawings: Figure 1—is a side elevation showing a tubular bracelet in closed position a portion being broken away at the joint to show the hinge member. Fig. 2—is an enlarged view showing a portion of the ends of the tubular sections as drawn apart in open position and partly in section showing the guard member mounted therein as limiting its opening motion. Fig. 3—is an enlarged sectional top view showing the ends of the tubular sections together and retained in position by my improved locking mechanism. Fig. 4—is a section on line 4—4 of Fig. 3 showing

one end of the guard member as soldered or retained in the tubular section. Fig. 5—is a perspective view showing the cup or thimble shaped member inserted into the end of one of the sections and slotted to receive and guide the guard member. Fig. 6—is a detail illustrating the preferred form of guard member having a pair of notched resilient fingers adapted to be engaged for retaining the ends of the sections together. Fig. 7—is a modification illustrating the guard as provided with one spring finger instead of two.

The bracelet is constructed of two hollow or tubular sections 10 and 11 connected together at 12 by a hinge joint of any preferred construction. It is found in the practical use of bracelets of this class that where the free ends are not limited in their opening motion that owing to the great leverage the joint portion is often bent or sprung and so rendered inoperative. To obviate this difficulty I have mounted an improved form of guard member 13 in the free ends of the tubular sections, said member being preferably constructed of thin flat spring metal and is arranged to limit the opening motion of these ends and to assist in guiding them one into the other as the bracelet is being closed. To further facilitate the interengaging of these two ends upon being closed, I have provided a tubular guide member 14, see Fig. 5, having its outer edge turned inward forming a lip 16 and leaving a slot or opening 15 through which the body of the guard is adapted to slide as the bracelet is opened and closed. The outer end of this tube 14 is arranged to extend a short distance beyond the end 11 of its section whereby it will enter the end of the opposite section to fit closely therein, and positively prevent lateral motion of these ends when the bracelet is closed.

My improved guard member is preferably provided with a pair of resilient fingers 17 and 18 which are formed integral with and are laterally extendible from opposite edges of said guard member. These fingers are provided near their free ends with cam-shaped edges 19 and 20 and are notched or recessed or depressed inwardly at 21 and 22.

The end 23 of this guard member adjacent these fingers, extends into and is fixed to the end of the tubular section 10 by solder,

swaging or other suitable means. The opposite end 24 of this guard through the slot 15 of the guide member 14 and the stock adjacent this end is preferably slit as at 25, see 5 Fig. 6, and the tongue 26 thus formed bent downward from the plane of the guard so that when the ends of the sections are drawn apart this tongue will abut the inner surface of the lip 16 of the guide member and limit 10 the opening motion of the bracelet. In closing the bracelet the inwardly turned lip portions 27 and 28 of the guide member 14 ride over the cam portions 19 and 20 of the fingers 17 and 18 pressing said fingers inward. These lips then enter the notched or 15 reduced portions 21 and 22 of these fingers thus providing a spring check or frictional detent to releasably retain these ends together whereby an excessive pull or unusual 20 strain on the ends of the sections will cause said fingers to yield inwardly and permit the lips 27 and 28 to ride over the cam-shaped edges and allow the bracelet to be opened. In my improved construction it will be seen 25 that the retaining mechanism is releasably held by a spring check or frictional detent whereby the free ends of the section may be readily drawn apart to open the bracelet without the necessity of operating an objectionable thumb nail presser pin for releasing 30 a positive locking mechanism, and yet my device is so constructed as to firmly retain said ends when moved to closed position.

35 I do not wish to be restricted to the provision of two spring fingers, one on either side of the guard member, as a single spring finger 30, as illustrated in Fig. 7, may be employed for this purpose if desired.

40 I have illustrated and described the bracelet as having its resilient retaining means carried by a guard member, but I do not wish to be restricted to the use of the guard member for this purpose, as the free ends of 45 the bracelet may be releasably connected together and retained by friction means constructed independent of said guard if desired.

I claim:

50 1. A bracelet comprising two tubular sections hinged together and having imperforate side walls, a guard member secured to

one section and provided with a resilient portion, a guide member secured to the other section and movable therewith to engage the 55 resilient portion of the guard member when the tubular sections are in closed relation to increase the tension upon the resilient portion sufficiently to provide a friction lock.

2. A bracelet comprising two tubular sections hinged together and having imperforate walls, a guard member secured to one section and provided with integral inwardly yielding spring fingers, and a guide member secured to and movable with the other 60 section and provided with an inwardly extending lip to engage said spring fingers when the two sections are in closed position to increase the tension upon said fingers sufficiently to provide a friction lock. 70

3. A bracelet comprising two tubular sections hinged together at one end and having imperforate walls, a guard member secured to one section and provided with one or more integral yieldable spring fingers having 75 curved ends therein, and a guide member attached to the other section and movable therewith, said guide member having an inwardly extending lip to engage said spring fingers when the sections are in closed position to increase the tension upon said fingers sufficiently to provide a friction lock, 80 said guard member having means co-operating with the guide member for limiting the separating movement of said sections. 85

4. A bracelet comprising two tubular sections hinged together, and having imperforate walls, a guard member secured to one section and provided with a resilient portion, an integral resilient stop finger, a guide 90 member secured to the opposite section and frictionally engaging said resilient portion when the two sections are in closed position, whereby the bracelet may be opened by a pull sufficient to overcome the frictional engagement, said guide abutting said stop finger when the sections are in open position. 95

In testimony whereof I affix my signature in presence of two witnesses.

EDGAR I. COOMBS.
